UNITED STATES PATENT OFFICE.

JOSEPH F. LOUGHREY, OF PHILADELPHIA, PENNSYLVANIA.

INKING MECHANISM FOR MULTIPLE-COLOR-PRINTING MACHINES.

Application filed April 7, 1926. Serial No. 100,234.

In my prior Patent No. 1,349,895, issued to me on August 17, 1920, I have described and broadly claimed a novel construction and arrangement of a multiple color printing press wherein a plurality of impression forms travel beneath an impression cylinder, and wherein inking mechanism is provided to apply to different forms ink of different colors.

This invention embodies the same general principle of operation as that of my patent aforesaid but relates more particularly to a novel construction and arrangement of inking mechanism for multicolor printing machines.

With the above in view, my invention comprehends novel inking mechanism for multicolor printing machines.

It further comprehends a novel construction and arrangement of inking mechanism, wherein inking rollers are arranged in sets, and wherein novel means are employed to move into and out of operative position one or more inking rollers which carry ink of a selected color.

It further comprehends a novel construction and arrangement of inking rollers, wherein the rolls are preferably arranged in sets, each set consisting of a desired number of pairs of rollers, novel means for raising and lowering a set, novel means for positioning the inking rollers of a set, and novel means for locking a pair of inking rollers when in operative position to apply ink of a selected color to a traveling impression form.

Other novel features of construction and advantage will hereinafter more clearly appear in the detailed description and the appended claims.

For the purpose of illustrating the invention, I have shown in the accompanying drawing a typical embodiment of it, which, in practice, will give reliable and satisfactory results. It is, however, to be understood that this embodiment is typical only and that the various instrumentalities of which my invention consists can be variously arranged and organized, and that the invention is not, therefore, limited to the precise arrangement and organization of these instrumentalities as herein set forth.

Figure 1 is a top plan view showing a portion of a multicolor printing machine, in conjunction with which an inking mechanism embodying my invention is employed, one set

of inking rollers having been removed for the sake of clearness of illustration.

Figure 2 is a side elevation of the inking mechanism.

Figure 3 is a section on line 3—3 of Figure 1.

Figure 4 is a section on line 4—4 of Figure 2.

Figure 5 is a section on line 5—5 of Figure 3.

Figure 6 is a section on line 6—6 of Figure 4.

Figure 7 is a front view of mechanism for locking a pair of inking rollers in inking position.

Figure 8 is a view similar to Figure 7 but showing the parts in a different relation from that seen in Figure 7.

Similar numerals of reference indicate corresponding parts.

Referring to the drawings:

As the construction and operation of a multiple color printing machine as illustrated and described in my prior Patent 1,349,895, is now well known in the art, I will illustrate and describe the general construction and operation of the machine with only sufficient detail to enable one skilled in this art to understand the construction and general operation.

The machine embodies an impression cylinder beneath which travels a series of impression forms carried by type beds, provision being made to provide a time interval to feed the paper to and from the impression cylinder during the continuous travel of the type beds. If, for example, four colors are to be printed five type beds are preferably used, and inking mechanism is provided to apply ink of a different color to each of the four impression forms carried by the type beds. The impression forms cooperate with the impression cylinder, so that during five revolutions of the impression cylinder four colors are printed, it being understood that the machine can be constructed and arranged to print any desired number of different colors.

1 designates the machine frame of a multiple color printing machine, in conjunction with which inking mechanism embodying my invention is employed. The frame is provided with an outer track 2 which carries the laterally extending antifriction rolls 3,

The frame is also provided with inner track ways 4 and 5 to guide the type beds 6 which carry the impression forms 7. These type beds 6 are connected together and are driven 5 in a similar manner to that disclosed in my prior patent to which I have hereinbefore referred.

With the inking mechanism illustrated, I employ five type beds 6, four of which carry 10 impression forms and one of which is not provided with an impression form. The inner tracks 4 and 5 form a path-way, which embodies a straight reach way 8 which passes beneath the impression cylinder 9 and a straight reach way 10 which passes beneath the inking mechanism. The straight reach ways 8 and 10 are connected by the curved end reaches 11 and 12, so that an endless, continuous path is formed in 15 which the type beds travel.

A main driving shaft 13 is suitably journaled in the machine frame and is provided with pulleys 14, thereby adapting it to be driven by any desired source of power. 20 The shaft 13 has fixed to it a gear 15, which meshes with a timing gear 16, fixed to a cam shaft 17.

The cam shaft 17, see Figure 2, has fixed to it one end of an arm 18, to which is connected one end of a link 19, the opposite end of said link being connected to a stud 20, carried by a quadrant 21, which is fulcrumed at 22 to the machine frame.

If only two colors are to be printed, I 25 employ but one set of inking mechanism, but, as in the present case, I contemplate printing four colors I employ two sets of inking mechanism 23 and 24 respectively, and each set is a counterpart of the other 30 and operates in the same manner, except as to its timing.

A link 25 is connected to the stud 20 of the quadrant 21, and also to a stud 26 of a quadrant 27 which is fulcrumed at 28 on 45 the machine frame. It will thus be seen that the quadrants are simultaneously operated. The quadrants at their peripheries are each provided with teeth 29, and with the cam faces 30 and 31 at opposite ends of such 50 teeth, a portion of the quadrant between such cam faces being cut away as at 32 in order to provide a clearance.

The teeth 29 of each quadrant mesh at 55 certain times with the teeth of a gear segment 33, each of which is loosely mounted on its respective rock shaft 34, suitably journaled in the machine frame.

Each rock shaft 34, see Figures 2 and 4, has loosely mounted on it one end of a rock arm 35 the free end of which is connected by a rod 36 to a disc 37 fixed to a shaft 38 journaled in an arm 39, forming part of a rock arm 40, fixed at its lower end to its respective rock shaft 34. Each 60 disc 37 has connected with it a rod 41 which

passes through a guide 42, carried by the rock arm 40, and, between such guide and a head 43 fixed to the rod 41, is interposed a tension spring 44.

In order that a pair of inking rollers 70 when in operative position will be locked in such position, each rock arm 35 is provided at its lower end with the shoes or bearing faces 45 and 46 and with a shoe or bearing face 47.

The foregoing mechanism is the mechanism employed for selectively positioning at the proper time a pair of inking rollers which carry ink of a selective color.

The main driving shaft 13 has fixed to it 80 a gear 48 which meshes with a gear 49 fixed to a shaft 50 suitably journaled in the machine frame.

The shaft 50 carries a sprocket wheel 51 around which passes a sprocket chain 52, 85 which latter, see Figure 2, passes also around a sprocket wheel 53 fixed to a shaft 54 journaled in the machine frame.

The shaft 54 is provided with a gear 55 which meshes with a gear 56 loosely mounted 90 on a rock shaft 34.

The gear 56 meshes with a gear 57, which latter meshes with the gear 58, which meshes with a gear 59 having elongated teeth and carried by a shaft 60, suitably journaled 95 in the machine frame. 61 designates a head journaled in the rock arms 40. This head has journaled therein in any desired manner a pair of inking rollers 62 and a pair of inking rolls 63.

The gear 59 has meshing with it a gear 64 fixed to a vibrating roll 65 which contacts with the peripheries of the inking rollers 62 to drive them. A gear 66 meshes with the gear 59 and is connected with a 105 vibrating roll 67 which contacts with the peripheries of a pair of inking rollers 63 to drive them.

The gear 59, see Figures 3 and 4, has meshing with it a pinion 68 fixed to a shaft 110 69 which carries a worm 70 which meshes with a worm wheel 71 fixed to a shaft 72 suitably journaled in the machine frame. This worm wheel 71 has eccentrically connected with it one end of a link 73, the opposite end of which is connected to a sleeve 74 which is slidably mounted on a rod 60.

The sleeve 74 is provided with the arms 76 which extend into the annular grooves 77 of the vibrating rolls 65 and 67 which are mounted on stationary rods 79. Each of the vibrating rolls contacts with the periphery of a pair of inking rollers so that during the revolution of such inking rollers the vibrating rolls have a reciprocating movement imparted to them and thus cause the ink to be uniformly distributed.

The inking rollers can be mounted in any desired manner and as illustrated, I have shown the ends of such rolls carried in jour- 130

nal boxes 80, which are slidable in the slots 81 in the brackets 82, which latter have preferably elongated slots 83 through which pass the fastening devices 84 which secure them 5 to the head 61.

The journal boxes 80 are adapted to have their position adjusted by means of manually actuated screws 85.

In order to rock the rock shaft 34 and 10 thereby the rock arms 40 in order to raise the inking rollers above the path of travel of the impression forms so that a pair of inking rollers of different color can be brought into operative position at the proper time with 15 one of the impression forms, I provide the following mechanism:

The cam shaft 17 has fixed to it a cam 86, see Figure 2, and this cam is provided with the cam faces 87 which co-operate with a 20 roller 88 carried by a lever 89, the upper end of which is fulcrumed at 90 to the machine frame. The lower end of the lever 89 has connected to it at one end a link 91 the opposite end of which is connected to one end of 25 an arm 92, the opposite end of which is fixed to a rock shaft 34 so that the left hand set of inking rollers seen in Figure 2, will at the proper time be raised and lowered.

The cam shaft 17 has also fixed to it a 30 cam 93, which is a counterpart of the cam 86, and which co-operates with an antifriction roller 94 fixed to a lever 95 the upper end of which is fulcrumed at 96 to the machine frame. The lower end of the lever 95 35 has connected to it one end of a link 97, the opposite end of which is connected to an arm 98 fixed at its opposite end to the rockshaft 34 which controls the raising and lowering of the other set of inking rolls, seen at the right 40 hand side of Figure 2.

99 designates the feeding table. The type beds are connected at their inner sides with each other by means of a link 100 and they are provided in a manner similar to that described in my prior Patent 1,349,895, with 45 racks 101. When the type beds are travelling over the straight course beneath the impression cylinder the length of each rack is such that they meet, and these racks are 50 driven by a single rack pinion in a similar manner described in my prior patent.

The inking fountains 102 are of any desired or conventional construction, and, as 55 illustrated, their ductor rolls 103 co-operate with the fountain rolls 104 which latter are provided with ratchets 105, with which engage the pawls 106 on the levers 107, said levers being operatively connected with the rock arms 108, each of which is connected by 60 means of a link 109 with its respective quadrant, such as for example, the quadrant 21.

It will thus be seen that during a movement of the quadrant, the fountain rolls will 65 be rotated step by step and as these rolls contact with the ductor rolls, the ductor rolls

are always provided with the desired amount of ink to be transferred to the inking rollers as such inking rollers of a set come into contact with their respective ductor rolls.

As I employ two pairs of inking rollers, I 70 employ superimposed ductor and fountain rolls, there being a set consisting of a ductor roll and a fountain roll for each pair of inking rollers.

The driving shaft 13 is intergeared with 75 the shaft of the impression cylinder 9, and a gear 110 meshes with a gear 111 which is fixed to a shaft 112 which carries a main driving pinion 113, which co-operates with 80 one of the racks of a type bed to cause a continuous travel of the type beds of the impression forms carried thereby so that the impression forms are successively brought into 85 co-operation with the impression cylinder 9 and the sheets carried thereby in the usual and conventional manner.

The shaft 50 carries a sprocket wheel 114 around which passes a sprocket chain 115 which passes around a sprocket wheel 116 corresponding in construction and function 90 to the sprocket wheel 55 so that it will be understood that each set of inking rollers are driven in the same manner so that a description of one will suffice for both and will be clear to those skilled in this art. 95

The operation of my novel inking mechanism for multiple color printing machines will now be apparent to those skilled in this art and is as follows:

Assuming that the main driving shaft 13 100 is being driven, it will be understood that the type beds 6, upon which are mounted the impression forms 7, travel in a continuous path.

One of these type beds does not carry an 105 impression form so that a sufficient time interval is provided to feed the sheets to and from the impression cylinder 9. The inking rollers are continuously driven, and a pair of them is successively brought into the 110 path of the impression forms, so that each of the impression forms will receive a different color of ink. As illustrated, the printing machine is adapted to print four colors, and, 115 for this reason, I employ four pairs of inking rollers, arranged in two sets with each set having two pairs of inking rollers.

The main driving shaft 13 is intergeared with the shaft 50, see Figures 1 and 2, thus 120 driving the sprocket wheels on said shaft, and thereby the sprocket chains 52 and 115, so that by means of the gears 55, 56, 57, 58, see Figure 4, and the gear 59, see Figure 2, the gears 64 and 66 will be driven and as the rolls 65 and 67 driven by said gears contact with the inking rollers 62 and 63, the latter will be continuously driven, as is apparent.

In the position of the parts seen in Figure 125 2, a pair of inking rollers 63 is being moved 130

in the direction of the arrow seen in Figure 2, to bring them into operative inking position with respect to an impression form. At this time it is necessary for the rock shaft 34 to be rocked outwardly, thereby raising the heads 61 so that sufficient clearance will be provided for bringing a pair of inking rolls into operative position. This movement of the heads 61 into and from operative position 10 is controlled by the cams 86 and 93.

As illustrated in Figure 2, one cam face 87 co-operates with the roll 88 causing the lever 89 to move towards the right, thereby drawing downwardly on the link 91, and rocking the shaft 34 in such a manner as to raise the head 61 at the left hand side seen in Figure 2.

The cam shaft 17 also controls the positioning of a pair of inking rollers which is 20 accomplished in the following manner:

The arm 18 is connected with the link 19 which is connected with the quadrant 21, and the quadrants 21 and 27 are connected by the link 25, so that these two quadrants 21 and 25 27 will be rocked in unison, on their fulcrum 22 and 28, respectively.

When a quadrant 21, for example, is rocked, the teeth 29 meshing with the teeth 39 of the gear 33 will rock the arm 35, thereby causing the link 36 to rotate the disc 37 in the proper direction to change the position of the head 61, and thereby of a pair of inking rollers so as to move such pair into or out of its operative position.

25 The periphery of each quadrant is cut away at 32 to provide a clearance for the lower end of an arm 35, and on the further movement of a quadrant, such as 21, it will be apparent that the bearing face 45 will ride up 40 on the cam 30, so that during the time an impression form is passing beneath a pair of inking rollers which are in operative position, such pair of inking rollers will be locked in operative position as will be understood by reference to Figure 7 and will also 45 be locked when in the reverse position, as seen in Figure 8.

When a pair of inking rollers are in inoperative position it will be locked in such position, due to the bearing faces 46 and 47 riding on the cam face 31 of its respective quadrant. The ink is supplied to the fountain in any desired or conventional manner.

50 The impression cylinder is intergeared with the shaft 13, thereby driven by it so that if four colors are to be applied the impression cylinder 9 has five revolutions imparted to it during the travel of the four impression forms beneath it.

55 As one pair of inking rollers move out of their operative position for inking an impression form, another set of rollers move into operative position to apply another color of ink to the next impression form.

60 Having thus described my invention, what

I claim as new and desire to secure by Letters Patent, is:

1. Inking mechanism for multiple color printing machines, comprising a set of inking rollers arranged in pairs, ink transfer mechanism for each pair of inking rollers, means to raise and lower said set and means to selectively oscillate each pair of inking rollers into and out of their inking position. 70

2. Inking mechanism for multiple color printing machines, comprising a set of inking rollers arranged in pairs, ink transfer mechanism for each pair of inking rollers, means to raise and lower said set, means to selectively move each pair of inking rollers into and out of their inking position, and means to effect the locking of each pair of inking rollers in the position to which such pair has been adjusted. 80

3. Inking mechanism for multiple color printing machines, comprising a plurality of sets of inking rollers, with the rollers arranged in pairs, ink transfer mechanism for each pair of inking rollers, means to raise and lower each set at predetermined intervals, and means to selectively oscillate each pair of inking rollers into and out of their inking position. 85

4. Inking mechanism for multiple color printing machines, comprising a set of inking rollers, ink transfer mechanism for said inking rollers, means to continuously revolve said inking rollers, means to raise and lower each set of inking rollers, and means to selectively oscillate the inking rollers. 95

5. Inking mechanism for multiple color printing machines, comprising a set of inking rollers arranged in pairs, ink transfer mechanism for each pair of inking rollers, means to raise and lower said set and means to selectively oscillate each pair of inking rollers into and out of their inking position, in combination with an impression cylinder, and means to feed a plurality of impression forms into operative relation with said inking rollers and said impression cylinder. 105

6. Inking mechanism for multiple color printing machines, comprising a set of inking rollers arranged in pairs, a tension device for said set, means to oscillate said set into and out of its operative position, and means to turn said set to selectively bring inking rollers carrying ink of different colors into and out of their inking position. 115

7. Inking mechanism for multiple color printing machines, comprising a set of inking rollers arranged in pairs, a head in which said set is journaled, means to raise and lower said head, means to continuously drive said rollers, means to selectively position a pair of rollers in inking position, and a reciprocating vibrating roller to cause a uniform distribution of ink on said inking rollers. 125

8. Inking mechanism for multiple color printing machines, comprising inking rollers arranged in pairs, a head in which said rollers are journaled, means to raise and lower said head, means to partially rotate said head to selectively position predetermined rollers in inking position, and cam means to lock said head in the position to which it has been adjusted.
- 10 9. Inking mechanism for multiple color printing machines, comprising a set of inking rollers arranged in pairs, a head in which said rollers are journaled, cam controlled means to effect the raising and lowering of said head, means to turn said head at predetermined intervals to selectively position the inking rollers in and out of their inking position, and means to lock said head to prevent its turning when an inking roller 15 is in its inking position.
- 10 10. Inking mechanism for multiple color printing machines, comprising a set of ink-
- ing rollers arranged in pairs, a head in which said rollers are journaled, a gear operatively connected with said head to turn it, a quadrant having teeth to mesh with said gear, and provided with cams to effect the locking of said head in the position to which it has been adjusted, means to actuate said quadrant, means to raise and lower said head, and means to effect the revolution of said inking rollers.
11. Inking mechanism for multiple color printing machines, comprising a plurality of sets of inking rollers with inking rollers arranged in pairs, means to effect at predetermined intervals the raising and lowering of each set, means to continuously revolve the inking rollers of each set, means to raise and lower each set, and means to turn each set in timed relation with the other to selectively position inking rollers in operative inking position.

JOSEPH F. LOUGHRY.
